UNITED STATES PATENT OFFICE.

ERNEST ALBION GROSS, OF LAMOILLE, MINNESOTA.

ARMAMENT FOR MAIL AND EXPRESS CARS.

Application filed May 24, 1922. Serial No. 563,298.

To all whom it may concern:

Be it known that I, ERNEST A. GROSS, a citizen of the United States, residing at Lamaille, in the county of Winona and State 5 of Minnesota, have invented certain new and useful Improvements in Armament for Mail and Express Cars, of which the following is a specification.

This invention relates to armament for 10 vehicles which are utilized for carrying valuables, such as mail and the like, and the primary object of the invention is to provide a novel device for use in connection with mail and express railway cars, which will 15 form an adequate protection for the mail or express messengers and guards and permit the messengers or guards to defend the car against bandits, without exposing themselves to danger.

Another object of the invention is the provision of a bullet proof box incorporated 20 with a mail or express car, the box having means for allowing the defenders of the car to shoot both inside and outside of the car, 25 so as to effectively permit the defense of the car both from bandits which may be on the inside or outside of the car.

Another object of the invention is the provision of a bullet proof steel box having 30 means for permitting the same to be extended out of the car a limited distance, so as to permit the defenders of the car positioned in the boxes to command approach to the car from the sides thereof, the box being of 35 such a size and configuration that the same when projected out from the car will not form obstructions to the car when the same is in motion.

A further object of the invention is the 40 provision of armaments for railway cars formed of bullet proof material, such as sheet steel of the desired gauge, and including defense boxes, the boxes being so constructed as to collapse against the side walls 45 of the car when the same are not in use, thereby forming a protecting device which will occupy a minimum amount of space in the car.

A further object of the invention is the 50 provision of a novel armament device for mail or express cars, which can be incorporated therewith at different points which may be found to be the most advantageous for the defense of the car, the novel armaments being of simple and durable construction.

With these and other objects in view, the invention consists in the novel construction, arrangement and formation of parts, as will be hereinafter more specifically described, 60 claimed and illustrated in the accompanying drawings, forming a part of this specification, in which drawings:

Figure 1 is a transverse section through a railway car showing the improved armament 65 devices incorporated therewith, one of the same being shown in collapsed inoperative position, and the other in its extended operative position.

Figure 2 is a fragmentary longitudinal 70 horizontal section through a railway car, showing a pair of improved armament devices incorporated therewith in plan, one of the devices being shown in collapsed inoperative position and the other in its extended 75 operative position.

Figure 3 is an inner or front elevation of one of the armament devices showing the same incorporated with a car.

Figure 4 is a vertical transverse section 80 through the armament device and car, taken on the line 4—4 of Figure 3, showing the armament device in collapsed or inoperative position.

Figure 5 is a vertical section through the 85 improved armament device taken on the line 5—5 of Figure 6, looking in the direction of the arrows and showing the locking means carried by the door of the improved device.

Figure 6 is a vertical section taken on the 90 line 6—6 of Figure 5 looking in the direction of the door and showing the locking means carried thereby.

Figure 7 is a horizontal section taken on the line 7—7 of Figure 5. 95

Referring to the drawings in detail, wherein similar reference characters designate corresponding parts throughout the several views, the letter A indicates a railway car; and B, the improved armament devices incorporated therewith. 100

The railway car A is of the usual construction with the exception that openings 10 are formed in the side walls 11 and 12 thereof to permit the armament devices B to 105 be extended out of the car as shown in Figures 1, 2, 5 and 7 of the drawings. The floor 13 of the car A also forms means for supporting certain parts of the improved armament devices B.

The armament devices B are disposed at 110 advantageous points on the car and in the

drawings two of the devices have been shown arranged directly opposite each other. As all of armament devices are constructed the same, only one will be described in detail.

- 5 The armament device B is preferably formed of bullet proof material, such as sheet steel of the desired gauge and consists of a rigid section C and a collapsible section D. The rigid section C has a width 10 substantially equal to the width of the side walls 11 and 12 of the car A with which the same is associated, and is adapted to be projected out of the car a sufficient distance to permit a person stationed within the 15 armament device to control approach to the car from the sides thereof. In actual practice, the distance which the rigid section C protrudes out of the car will only be about six inches or less and thus the armament 20 device may be extended when the car is in motion without the likelihood of the same coming into contact with objects facing alongside of the track.

This rigid section C includes side walls 25 and 16, bottom and top walls 17 and 18, and a front wall 19. The front wall 19 can be provided with a face plate 20, the edges of which can protrude beyond the front wall to provide stop flanges 21 for engaging 0 against the outer face of the side walls of the car when the armament device is in its retracted inoperative position as clearly shown in Figure 4 of the drawings. These flanges 21 not only constitutes stops, but 5 also constitute means for forming a tight joint between the armament device and the outer face of the car. The side walls 15 and 16 and the top and bottom walls 18 and 17 can be connected in any preferred manner to the front wall 19 and as shown, these walls are formed integral with the front wall.

The collapsible section D consists of side walls 25 and 26, bottom and top walls 27 and 28, and a front wall or door 29. The side walls 25 and 26 are connected respectively to the rigid side walls 15 and 16 of the section C by means of hinges 30 and 31, and these walls are adapted to close inwardly to permit the collapsing of the device B. The wall 25 is first folded inwardly, after which the wall 26 is swung into engagement therewith and in order to permit these walls to lie flat into engagement with each other, the rigid wall 15 of section C is formed narrower than the rigid wall 16 which of course, sets the wall 25 inwardly of the wall 26, and necessitates the same being made wider than the wall 26. The front wall or door 29 is connected by means of hinges 32 to the outer edge of the side wall 26 and when the device B is in its extended position, this wall is adapted to engage the free or outer edge of the wall 25. The upper and lower edges of the wall or door 29 at the free longitudinal

edge thereof is provided with inwardly extending flanges 33 for engaging the side wall 25 and the bottom and top walls 27 and 28. If so desired, the upper and lower edges of the side walls 25 and 26 can be provided with 70 inwardly extending flanges 34 which constitute stops and rests for the upper and lower walls 28 and 27 as will be now described. The upper and lower walls 28 and 27 are connected by strap hinges 35 and 36 with 75 the front wall 19 of the rigid section C, adjacent to the lower and upper ends thereof. The leaves of the hinges 35 and 36 are formed relatively long so as to permit the lower and upper walls 27 and 28 to be swung 80 into flush engagement with the rigid lower and upper walls 17 and 18 of the section C when the armament device B is in its extended position.

If so desired, the outer edges of the lower and upper walls 27 and 28 may be offset as at 37 in order to permit the engagement of the flanges 34 formed on the side walls 25 and 26 and the flanges 33 formed on the front wall 29 therewith when the armament device is in its extended position. Suitable pivoted latches 38 are carried by the side walls 25 and 26 adjacent to the upper and lower ends thereof for engaging the offset edges 37 of the lower and upper walls 27 and 28 when the armament device is in its extended form for holding the said lower and upper walls 27 and 28 against movement. These latches clamp the lower and upper walls 27 and 28 between the flanges 34 and effectively holding the upper and lower walls in engagement therewith against movement. The upper and lower walls 28 and 27 are adapted to be folded prior to the folding of the side walls 25 and 26 and these 100 walls 27 and 28 lie flush up against the rigid front wall 19 of the rigid section C as clearly shown in Figure 4 of the drawings when the armament device is in its collapsed inoperative position. The front wall or door 110 29 of the collapsible section C is folded back against the side walls 26 when the side walls are in their folded position as clearly shown in Figure 4 of the drawings. This forms a 115 relatively flat construction and the device will occupy a minimum amount of space when in its collapsed position.

A locking means E is provided for holding the door or front wall 29 in its closed position and the device against collapsing 120 movement when the same is in its extended position, and the locking device includes locking bolts 40, 41 and 42. The bolts 40 and 41 are disposed in vertical alignment and are slidably mounted in guides 43 carried by the front wall or door 29 and these bolts are adapted to protrude through registering openings in the lower and upper walls 27 and 28 adjacent to the outer edges thereof and in the flanges 33 formed on the front 130

wall 29. The bolt 42 is formed relatively short and is also slidably mounted within a guide 44 carried by the front wall and is adapted to protrude through registering 5 openings formed in the side wall 25 and the vertical flange 34 formed on the front wall or door 29. These bolts are adapted to be actuated by links 45, 46 and 47, which are pivotally connected to the terminals of the 10 double ended actuating lever 48, which is mounted at a point equi-distant its ends upon a rotatable stud 49 carried by the front wall or door 29. This stud is provided with an operating handle 50 and it is obvious 15 that when this handle 50 is turned, the bolts will be brought inwardly or outwardly according to the direction in which the handle 50 is turned.

A means F is provided for moving the 20 armament device B into extended and retracted position in relation to the side wall of the car and this device F includes an operating shaft 55, which is mounted for rotary movement within suitable bearings 56, 25 which are secured in any preferred manner to the floor 13 of the car A. This shaft 55 is operatively connected to vertically disposed counter shafts 57 and 58 by means of bevelled gearing 59, and these shafts are 30 located on opposite sides of the armament device B as clearly shown in Figure 3 of the drawings. These counter shafts 57 and 58 are rotatably mounted in suitable bearings 60 carried by the inner face of the side wall 35 of the car A. The lower rigid wall 17 of the section C of the device B supports inwardly extending rack bars 61 and 62, which are adapted to be operatively engaged by gear wheels 63 keyed or otherwise secured to the 40 operating shaft 55. The side walls 15 and 16 of the rigid section C also support inwardly extending rack bars 64 and 65 which have meshing therewith gear wheels 66 and 67 which are keyed or otherwise secured respectively to the counter shafts 57 and 58. 45 Thus it can be seen that when the shaft 55 is turned, the device A will be projected out of or drawn into the car A according to the direction of rotation of the said shaft. The 50 means for actuating the shaft 55 includes an operating lever 68 which has its lower end bifurcated as at 69 and mounted upon the shaft 55 for swinging movement. The shaft 55 also has keyed or otherwise secured 55 thereto a relatively broad ratchet wheel 70' which is disposed in the bifurcated portion 69 of the operating lever 68. The opposite sides of the lever 68 at the bifurcated portion 69 thereof carries sets of pawls 70 and 71 and these sets of pawls 70 and 71 are connected by means of links 72 and 73 to a rocking actuating handle 74. The rocking operating handle 74 is operatively connected to the operating lever 68 by means of a 65 pin 75.

When desired to extend the armament device B outwardly of the car, the handle 74 is rocked in the appropriate direction for lifting one of the set of dogs 70 or 71 from out of engagement with the ratchet wheel 70' and the lever 68 is then rocked which will turn the shaft 55 in the desired direction for moving the armament device B outwardly. When desired to move the armament device B inwardly, the 75 handle 74 is rocked in the opposite direction as is the lever 68. The walls of the armament device B are provided at appropriate points with loop holes 80 which permit a person stationed in the armament device to fire out of the same into the body of the express car and outwardly out of the body of the express car.

It is also preferred that the armament device be provided with suitable gun racks 85 where guns can be conveniently at hand.

In normal times, the armament devices B are disposed in their collapsed position so that they will occupy a minimum amount of space, but in times of danger, the collapsible side walls 25 and 26, the lower and upper walls 27 and 28 are swung to their extended positions and the front wall or door 29 moved to its closed position. The guard or messenger then operates the lever 68 for 90 moving the armament device outwardly of the car, after which the guard or messenger can step into the same and operate the lock E for closing the armament device B against access by unauthorized persons. It now 95 can be seen that the guard or messenger is completely shut off from all parts of the express or mail car and is fully protected by the bullet proof walls of the armament device, and he is permitted to fire out of the same in order to protect the car from assault.

Changes in details may be made without departing from the spirit or scope of this 100 invention; but,

I claim:

1. The combination with a railroad car, of an armament device therefor including a bullet proof box slidably associated with the car for moving exteriorly and interiorly thereof.

2. The combination with a vehicle, of an armament device incorporated therewith including a bullet proof collapsible box slidably associated with the vehicle having loop holes therein.

3. The combination with a vehicle including a body having an aperture therein, of an armament device including a bullet proof box slidably associated with the body of the vehicle arranged for movement through the said aperture exteriorly of the body.

4. The combination with a railway car including a body, the side walls of which are provided with openings, of an arma- 130

ment device for the car including a rigid section and a collapsible section, means slidably associating the rigid section with the walls of the opening formed in the body of the car, and means for sliding said rigid section for moving the same exteriorly of the body section of the car.

5. The combination with a railway car having side walls, of an armament device therefor comprising a bullet proof box including a rigid section, and a collapsible section, the collapsible section consisting of side walls hingedly connected to the rigid section, top and bottom walls hingedly connected to the rigid section, and a door hingedly secured to one of the side walls of the collapsible section.

6. The combination with a railway car including a body having side walls, of an armament device slidably associated with the side walls including a bullet proof box having a rigid section, and a collapsible section, the collapsible section including swinging side walls, and swinging top and bottom walls hingedly connected with the rigid section, a front wall hingedly connected to one of the side walls, and catches carried by the inner surface of the side walls for holding the collapsible section in its extended operative position.

7. The combination with a railway car including a body having side walls, of an armament device slidably associated with the side walls including a bullet proof box having a rigid section, and a collapsible section, the collapsible section including swinging side walls and swinging top and bottom walls hingedly connected with the rigid sec-

tion, a front wall hingedly connected to one of the side walls, catches carried by the inner surface of the side walls for holding the collapsible section in its extended operative position, and a three bolt lock carried by the front wall for locking engagement with one of the side walls and the top and bottom walls.

8. The combination with a railway car including a side wall having an opening therein, of an armament device comprising a bullet proof box slidably associated with the walls of the opening and including a rigid section having a front wall and inwardly extending side, top and bottom walls, inwardly extending rack bars carried by the rigid section, a collapsible section hingedly connected with the rigid section, an operating shaft, a lever for rotating the operating shaft in either direction, and gear wheels operatively connected with the operating shaft for engaging the rack bars.

9. The combination with a railway car having a side wall provided with an opening, an armament device including a bullet proof box slidably associated with the walls of the opening, and arranged to be projected exteriorly of the same a limited distance including a rigid section having a front wall and inwardly side, bottom and top walls, means for sliding the rigid section in relation to the wall of the car, and a face plate carried by the front wall of the rigid section having its marginal edges extending beyond the front wall for engagement with the outer face of the side wall of the car.

ERNEST ALBION GROSS.
